US0D1107656S

(12) **United States Design Patent** (10) **Patent No.:** **US D1,107,656 S**
(45) **Date of Patent:** **** Dec. 30, 2025**

(54) **SOCKET**

(71) Applicant: **JOININ GLOBAL PTE. LTD.,**
Singapore (SG)

(72) Inventor: **Hongbing Zheng**, Singapore (SG)

(73) Assignee: **JOININ GLOBAL PTE. LTD.,**
Singapore (SG)

(**) Term: **15 Years**

(21) Appl. No.: **29/907,317**

(22) Filed: **Jan. 5, 2024**

(51) LOC (15) Cl. **13-03**

(52) U.S. Cl.
USPC **D13/139.6**

(57) **CLAIM**

The ornamental design for a socket as shown and described.

DESCRIPTION

FIG. 1 is a front perspective view of a socket showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and

FIG. 9 is an enlarged view of portion 9 in FIG. 1; and,

FIG. 10 is an enlarged view of portion 10 in FIG. 1.

The dash-dash broken lines depict portions of the socket that form no part of the claimed design. The dash-dot-dash broken lines shown in FIGS. 1, 9 and 10 depict the boundaries of the enlarged areas and form no part of the claimed design.

1 Claim, 10 Drawing Sheets
